UNITED STATES PATENT OFFICE.

HIRAM SWART DOTTs, OF THOBURN, WEST VIRGINIA, ASSIGNOR OF ONE-FIFTH TO JULIA D. SCHUTTE, OF FARMINGTON, AND JOHN F. REGULSKI, OF MONONGAH, WEST VIRGINIA.

MECHANIC'S TRESTLE.

SPECIFICATION forming part of Letters Patent No. 617,463, dated January 10, 1899.

Application filed December 27, 1897. Serial No. 664,607. (No model.)

To all whom it may concern:

Be it known that I, HIRAM SWART DOTTs, a citizen of the United States, residing at Thoburn, in the county of Marion and State of West Virginia, have invented a new and useful Plan or Device for the Construction of Mechanics' Trestles, of which the following is a specification.

This invention relates to mechanics' trestles, and particularly to a clamping device by which the supporting-legs may be connected to the beam and also extensions secured to said legs.

The invention has for its object to provide a construction of clamp which may be readily applied to beams of different sizes and adjusted so as to firmly connect the supporting-legs to said beams.

It has as a further object to supply a construction having the minimum number of parts and which may be applied quickly by the ordinary mechanic, so as to avoid delay in erecting scaffolding.

A further object of the invention is to provide an adjustable clamp for connecting extension-pieces to the supporting-legs, whereby the beam of the trestle will be adjusted to different vertical elevations.

Other objects and advantages of the invention will hereinafter appear in the following description, and the novel features thereof will be particularly pointed out in the appended claims.

In the drawings, Figure 1 is a perspective illustrating the clamping-plates applied and also the leg-adjusting device. Fig. 2 is a detail perspective of one of the clamping-plates. Fig. 3 is a similar view of the co-operating plate. Fig. 4 is a plan of the clamping device for the leg. Fig. 5 is a perspective of the connecting-plate. Fig. 6 is a similar view of the wedge-block. Fig. 7 is a detail perspective of the upper surface of the beam, and Fig. 8 is a vertical cross-section through the clamping-plates when assembled.

Like letters of reference indicate like parts throughout the several figures of the drawings.

The letter A designates the beam or timber

to which the legs B are to be connected. If 50 this beam be of greater size than the clamping-plates, it may be provided upon its upper surface with a recess A'. This, however, is not necessary when the proper size of beam and plates are used. The legs B are beveled, 55 as at B', upon their inner upper face.

For the purpose of detachably connecting the legs to the beam I provide clamping-plates C and C', each of which is cut away at its central portion, as at C², to provide an 60 aperture through which connecting means may pass. The outer face of each of the plates C and C' is provided with leg-retaining keepers C³ and C⁴, the outer wall of which inclines inwardly toward the plate. The 65 keeper C⁴ is of greater length and also extends a greater distance away from the plate, so as to accommodate the inclination of the outer face or surface of the leg when inserted therein. The plate C is provided at its lower 70 portion with one or more lateral extensions C⁵, which lie beneath the surface of the beam and are provided upon their under faces with projections which form recesses C⁶. The opposite plate C' is provided at each side with 75 apertures C⁷, which leave a finger C⁸, adapted to seat in one of said recesses C⁶ when adjusted to the proper width of the beam A. For the purpose of connecting the upper 80 ends of the plates C and C' a connecting-plate D has been provided at one end with an upwardly-extending flange D' and at the opposite end with a series of projections or ribs D², which form recesses D³, in which the upper edge of the opposite plate is adapted 85 to seat. The lower face of this plate may be slightly curved, as at D⁴, and beneath the same the wedge-block E is driven. This block has an inclined surface E' upon its upper face, which when in contact with the curved face 90 D⁴ forces the connecting-plate D upward, thus securely holding the opposite clamping-plates together and drawing the lower portion of the plate C' into one of the recesses C⁶ provided upon the opposite plate.

For the purpose of connecting an extension-piece B² to the leg B, I provide the flexible clamping-band F, which may be formed

of wire or other suitable flexible material. One end of this band is provided with a head F', passed through a brace-plate G, the opposite end of which is provided with a slightly inclined slot G', which permits the introduction and removal of the opposite end of the band F. The plate is formed of increased thickness on opposite sides of the slot G', as indicated at F⁴, which prevents the band 5 from lateral displacement. This end of the band is provided with a permanent head F² and with a series of washers F³, slidingly mounted upon the band, so that they may be located upon either side of the bracing-plate 10 G, and thus adjust the length of the band in its relation to the plate. Beneath the brace-plate G a bearing-block B³ may be located, and threaded through this plate is an adjusting-screw H, provided at its inner end with 15 a bearing-disk H', having thereon a holding-point H². The outer end of this screw is provided with a suitable head H³, the rotation of which will force the brace-plate G away from the bearing-block, and thus tighten 20 the band F and firmly connect the leg and extension-piece.

I have described in detail the preferred construction of the several parts; but it is obvious that changes may be made in the details thereof without departing from the spirit 30 of this invention, as defined by the appended claims.

What I claim, and desire to secure by Letters Patent of the United States, is—

- 35 1. In a trestle, oppositely-located independent clamping-plates adapted to engage a beam, adjustable plates provided with recesses engaging the upper and lower portions of said clamping-plates, and leg-retaining 40 keepers upon the outer faces of said plates; substantially as specified.
- 45 2. In a trestle, oppositely-located slotted clamping-plates adapted to engage a beam, an extension upon the lower portion of one plate adapted to engage the opposite plate, and securing devices passing through said slots to connect the upper ends of said plates, and means for attaching supporting-legs to said plates; substantially as specified.
- 50 3. In a trestle, a clamping-plate provided with a lateral extension at its lower edge, an opposite clamping-plate adapted to engage said extension, an adjustable recessed plate connecting the upper portion of said clamping-plates together, and means for attaching 55

supporting-legs to said plates; substantially as specified.

4. In a trestle, a clamping-plate provided with a lateral extension having recesses upon its lower face, an opposite plate provided with apertures through which said extensions pass, and a wedge-block bearing upon the upper portion of said plates; substantially as specified.

5. In a trestle, a clamping-plate provided 65 with a lateral extension having recesses upon its lower face, an opposite plate provided with apertures through which said extensions pass, a wedge-block bearing upon the upper portion of said plates, and a connecting-plate 70 at the upper portion of said clamping-plates held by said wedge; substantially as specified.

6. In a trestle, a clamping-plate provided with a lateral extension having recesses upon 75 its lower face, an opposite plate provided with apertures through which said extensions pass, a wedge-block bearing upon the upper portion of said plates, and a connecting-plate having ribs or projections upon its upper surface and held in contact with said clamping-plates by said wedge; substantially as specified.

7. In a trestle, the combination with a leg, of an extension-piece, a brace-plate, a flexible 85 band having its opposite ends secured to said plate, a tension-screw threaded in said plate, and a series of washers slidingly mounted on said clamping-band; substantially as specified.

8. In a trestle, the combination with a leg, of an extension-piece, a brace-plate, a flexible band having its opposite ends secured to said plate, a tension-screw threaded in said plate, a series of washers slidingly mounted on said 95 clamping-band, and a bearing-plate upon said tension-screw; substantially as specified.

9. In a trestle, the combination with a supporting-leg, of an extension thereto, a bracing-plate provided with a slot at one end and 100 of increased thickness adjacent to said slot, a flexible band having enlargements at its ends one of which is removably held in said plate, and a tension-screw threaded in said plate; substantially as specified.

HIRAM SWART DOTT.
